CLAIM

The ornamental design for a shower surround, as shown and described.

DESCRIPTION

FIG. 1 is a perspective view taken from the top front and left side of a shower surround showing our new design;

FIG. 2 is a perspective view taken from the top, front and right side thereof with the transparent front removed for convenience of illustration;

FIG. 3 is a front elevational view thereof; and,
FIGS. 4, 5, 6 and 7 are cross-sectional views, taken on lines 4—4, 5—5, 6—6 and 7—7, respectively, of FIG. 3, with the transparent front removed.
